UNITED STATES PATENT OFFICE.

THOMAS M. RINEHART, OF DALLAS, TEXAS.

COMBINATION MUFFLER AND AIR-HEATING DEVICE.

1,280,847.

Specification of Letters Patent.

Patented Oct. 8, 1918.

Application filed August 20, 1917. Serial No. 187,150.

To all whom it may concern:

Be it known that I, THOMAS M. RINEHART, a citizen of the United States of America, residing at Dallas, in the county of Dallas, State of Texas, have invented a certain new and useful Improvement in Combination Mufflers and Air-Heating Devices, of which the following is a specification.

This invention relates to a new and useful form of muffler for silencing the explosions due to the exhaust of internal combustion engines and embodies a means for heating fresh air for use in facilitating the carburetion of liquid fuel oil to a combustible gaseous mixture.

An object of the invention is to provide a combined form of automobile engine muffler and fresh air heating device which will comprise an inclosed chamber with suitable air passages, and which device may be interposed at any convenient point in the exhaust tube which leads from the engine to the rear of the automobile. The device includes means for connecting the usual form 25 of fuel oil carbureter with an outlet air duct of the heating device.

With the above and other objects in view the invention has relation to a certain combination and arrangement of parts, an example of which is described in the following specification, pointed out in the appended claims and illustrated in the accompanying drawings; wherein,

Figure 1 illustrates a longitudinal sectional view of this combined automobile engine muffler and air heater for carbureter.

Fig. 2 illustrates a cross sectional view of said device.

Referring now more in particular to the drawings, the numeral 1 designates a pair of metal disk heads spaced apart and supporting a plurality of tubular members 2, which tubes have each extremity thereof formed open. A cylindrical shell 3, provided with suitable flanges formed on the extremity thereof, is carried between the disk heads 1, while a second cylindrical shell 4 is placed upon the heads concentrically with the shell 3. This assembly of parts 45 provides an annular space 5 between the walls of the two shells passing around the said device. The shell 3 is provided with a plurality of inlets 6 which allow communication between the chamber 5 and the 50 interior of the device. A partition or baffle plate 7 is centrally located within the in-

closed chamber and supported between the heads thereof in any suitable manner. The baffle plate is provided with openings 8 of required number and size. The openings 60 will preferably be formed in the baffle plate near one end thereof while the openings 6 will preferably be formed in the shell at the opposite end thereof.

Closure heads comprising a substantially 65 large flanged member 9 are fixed upon the extremities of the heating muffler in any suitable manner and, as is illustrated, are fixed to the disk heads by bolts 10 passing through the several parts to be held. The 70 heads 9 are provided with tubular extensions 10a.

An air duct 11 is passed through the outer shell 4 and has direct attachment with the inner shell 3. A tube 12, which will preferably be of a diameter slightly increased over that of the duct 11 is connected to the tube 12 through a reduction coupling 13. The member 12 carries a coil 14 which has its two extremities extended upwardly through 80 openings in the tube 12. One of the threaded extremities of the tube will be connected to the pipe leading to the fuel tank of the car, while the other tube will be connected to the carbureter in the usual manner.

This muffler heating device is provided with the tubular extensions 10a for the purpose of connecting it into the exhaust manifold. The exhaust gases pass into one head 90 and on through the many tubes 2 and out of the muffler through the other head into the exhaust tube. The plurality of thin wall tubes 2 serve to absorb and take up the heat from the exhaust which passes outwardly 95 through the other head into the exhaust tube or atmosphere.

A substantially large opening 15 is formed in the shell 4 for the purpose of admitting fresh air into the annular space 5. 100

The tube 12 will be connected up with the carbureter of the engine and during the running of the motor a considerable suction and draft is set up through the tube and duct 11 passing all the way between and 105 around the plurality of tubes 2. This serves to draw the air from the enlarged opening 15 around the annular space 5, formed between the two shells 3 and 4 and into the openings 6. The deflector plate 7 causes the 110 air to traverse the longitudinal length of the device and direct same through the openings

8 and into the duct 11. After the air has taken the course as described it has passed in contact with many square feet of heating surface and has a high calorific capacity.

5 The hot air passing through the duct 11 and tube 12 heats the coil 14 which raises the temperature of the fuel oil before it passes into the carburetor to a high degree.

The use of this combined form of muffler 10 and generator on an automobile effectively provides a combined device which will muffle the sound of the engine without creating a back pressure and will also increase to a marked degree the efficiency of economy 15 of the engine.

The invention is presented to include all changes and modifications in design and form as may be construed to come within the meaning of the following claims.

20 Claims.

1. In a combined form of heating device and muffler, the combination with a pair of cylindrical shells one of less diameter than the other concentrically arranged with an 25 annular space formed therebetween and an opening to permit air to pass into this annular space, of a plurality of heating tubes with open extremities arranged interiorly of the smaller shell, and closure heads to 30 connect the tubes with the exhaust manifold of an engine, and a duct connecting with one of the shells adapted to convey fresh heated air therefrom and supporting means to retain the heating tubes.

35 2. In a combined form of muffler and

heating device, the combination with suitable disk heads, of a plurality of heating tubes disposed therebetween, of a pair of concentrically arranged shells arranged around the heating tubes and providing an 40 annular chamber therebetween and an enlarged opening from the atmosphere into the annular chamber, a baffle plate with openings therein fixed within the inner shell, and a hot air duct connecting with the inner 45 shell for drawing off warm air for any desired purpose, closure heads for the outer shell, and provision for connecting the device up with the exhaust manifold of an engine. 50

3. In a combined form of heating device and muffler for silencing the sound of an engine and heating air for use in carbureting fuel for the same engine, the combination with a pair of concentrically arranged 55 shells with suitable opening in the outer shell to communicate with the atmosphere, a plurality of heating tubes arranged interiorly of the inner shell, and closure heads with tubular extensions fitted on each end 30 of the outer shell for connecting the heating device into the exhaust pipe of an engine, and a duct connecting with the inner shell of the heating device for drawing off 35 warm air and closure heads provided to connect the device in with the manifold of an engine. 85

In testimony whereof I hereunto affix my hand.

THOMAS M. RINEHART.
